UNITED STATES PATENT OFFICE.

NEAL T. MCKEE, OF MOUNT VERNON, NEW YORK, ASSIGNOR TO THE SUPERHEATER COMPANY, OF NEW YORK, N. Y., A CORPORATION OF DELAWARE.

FEED-WATER HEATER.

Application filed October 3, 1923. Serial No. 366,231.

To all whom it may concern:

Be it known that I, NEAL T. MCKEE, a citizen of the United States of America, and a resident of the city of Mount Vernon, 5 Westchester County, State of New York, have invented certain new and useful Improvements in Feed-Water Heaters, of which the following is a specification.

This invention relates to feed water heaters and more particularly to that type of feed water heaters designed for use upon steam locomotives. In this type of heater a plurality of small copper tubes are located within an outer steam casing or jacket and 10 are suitably secured to and extended between a pair of headers, one of which is fixed to the casing at one end thereof and the other of which is freely floating at the other end, the steam being admitted to said casing to surround the tubes and heat the feed water passing therethrough.

The feed water is pumped under pressure into a suitable water space in the fixed header, which water space communicates 15 with a lower quadrant of tubes to conduct the water to the header at the opposite end of the casing, and passes through a water chamber in the floating header to a second quadrant of tubes immediately above the 20 first quadrant. The second quadrant of tubes leads the water back to a second water space of the fixed header which leads it to the adjacent upper or third quadrant of tubes, through which it flows back to a second 25 water chamber in the floating header, which delivers it to a fourth quadrant of tubes from which it passes through the fixed header to a feed pipe which carries water to the boilers.

Great difficulty has been experienced with 30 this type of feed water heater in maintaining a steam tight joint between the small copper water tubes and the headers because of the unequal expansion of the tubes, it being obvious 35 that the water within each quadrant of tubes is at a different temperature, consequently a twisting strain is produced upon the floating header, this strain being at a maximum between the first and fourth 40 quadrants. In order to overcome this twisting strain due to the differences in expansion caused by the unequal temperatures in each quadrant, the floating header has been divided vertically into two equal halves 45 each of which is connected with one-half

of the total number of tubes, one half-header thus formed being connected with the first and second quadrants of the tubes and the other half-header being connected with the third and fourth quadrants. 60 While this expedient has resulted in decreasing to a certain extent the twisting strain upon the floating headers and the loosening of the tubes due to unequal expansions, it has not altogether overcome the 65 loosening of the tubes, as a further loosening thereof is caused by tension produced upon the tubes by unbalanced water pressure within the headers, tending to cause said headers to move away from each other 70 longitudinally of the tubes.

The principal object of this invention is to provide a new and improved construction in a feed water heater of the type described by means of which the tension upon the 75 tubes due to unbalanced water pressures within the headers is removed.

Another object is to provide the floating header with a movable cylinder capable of transmitting the force due to unbalanced 80 pressures within the headers to the outer steam casing, thereby removing the tension upon the tubes.

For the accomplishment of these and such further objects as will hereinafter be 85 apparent to those skilled in the art to which this appertains, the invention consists in the construction, combination and arrangement of parts, a preferred embodiment of which is hereinafter specifically described and is 90 illustrated in the accompanying drawing, but it is to be understood that changes, variations and modifications may be resorted to without departing from the spirit of 95 my invention. In the drawing forming a portion of this specification and wherein like reference characters designate corresponding parts throughout the several views,

Fig. 1 is a side elevation partly in section 100 of a feed water heater of the type disclosed and embodying my invention;

Fig. 2 is a section on the line 2—2 of Fig. 1;

Fig. 3 is a section on the line 3—3 of 105 Fig. 2; and

Fig. 4 is a section on the line 4—4 of Fig. 2.

Referring to the drawing 10 indicates the outer steam casing or jacket to one end of 110

which the fixed header 11 is secured. Suitably secured to the header 11 and extending longitudinally within the casing are a plurality of small copper water tubes 12, 5 the other end of which tubes are secured to a pair of floating half headers 13 as heretofore described. The header 11 is provided with suitable dividing walls to direct the water from the inlet pipe 14 through 10 the first quadrant of tubes to the floating half header 13 shown at the right of Fig. 2, passing upwards through water chamber 15 of said header to the second quadrant of tubes, back to header 11, thence horizontally 15 through water chamber 16 thereof to the third quadrant of tubes upon the left hand side (Fig. 2) of the heater. The water then passes through the third quadrant of tubes to the upper part of the water chamber 15 20 of the left hand header 13 and downwardly therethrough to the fourth quadrant of tubes, through which it flows to an outlet pipe (not shown) in the header 11, similar to the pipe 14, to be led thereby to the 25 boiler.

As the water within the water chambers is under pressure, there would, as inspection of Figs. 2 to 4 inclusive will clearly show, be an unbalanced pressure upon the outer 30 walls of the water chambers 15, 15, in the direction of the arrow A in Fig. 4, with consequent strain upon the tubes 12, unless provision were made to balance such pressure; this unbalanced pressure upon each of the 35 floating half headers 13 would obviously be equal to the pressure upon an area equal to one-half of the combined cross sectional area of the tubes 12. In the particular construction shown, tension would be exerted directly upon the expanded joints 17 by means of which the tubes 12 are connected with the headers 13. In order to eliminate this tension, the following means are provided: Each of the floating half headers 13 is provided centrally thereof with a boss 18, which 40 is provided with a bore 19, communicating directly with the water chamber 15. The bore 19 is screw-threaded to receive a reduced apertured boss 20 of an inner guiding sleeve 21 provided as at 22 with suitable packing. A movable cup shaped cylinder 23 is slidably mounted upon the guiding sleeve 21 and the inner diameter of said cylinder is so proportioned that the cross 45 sectional area of the cylinder will be equal to the combined cross sectional area of the tubes connected to its respective header. The end closure 24 of the outer casing is provided with a pair of bosses 25 as shown 50 in Figs. 3 and 4 each of which is in alignment with the axial center of its cooperating cylinder 23 to receive the thrust of the cylinders.

The operation of the device is as follows: 55 when the water under pressure enters the

water chambers 15 of the floating headers, the water will pass through the apertured bosses 20 of the guiding sleeves 21 and will force the cylinders 23 outwardly into contact with the bosses 25, the thrust of each 70 cylinder being communicated to the end closure 24 of the outer casing, from which it is transmitted through the bolts 27 to the outer casing 10, the bosses 25 thus forming means to transmit to the casing the outwardly directed pressure exerted by the water upon the movable walls formed by the ends of the cylinders 23. Many other means for transmitting this pressure to the casing may obviously be substituted for the 75 bosses 25 without departing from the principles of my invention. As the main or fixed header 11 is secured to the outer casing, it will thus be seen that the entire thrust due to the pressure of the cylinders 80 23 will be in effect tied to the fixed header, and as the combined area of both the cylinders 23 is equal to the combined area of all the tubes 12, that the tension due to the unbalanced pressure in the water chambers 85 is entirely removed from the tubes.

While I have shown my invention as applied to a feed water heater having a pair of floating half headers, it will be apparent that the same principles of construction 90 could be applied to a single floating header or to a heater having more than two floating headers.

I claim:

1. In a feed water heater having an outer 100 steam casing, a main header and a floating header therein and a plurality of water tubes secured to and extending between said headers, said headers being provided with water chambers with which said tubes are 105 in communication and means to transmit to said casing outward strains due to unbalanced water pressure within said floating header, whereby tension upon said tubes due to such unbalanced pressure is prevented.

2. In a feed water heater having an outer steam casing, a main header and a floating header therein and a plurality of water tubes secured to and extending between said headers, said headers being provided with 110 water chambers with which said tubes are in communication, and means defining a chamber secured to said floating header and communicating with the water chamber thereof, a movable wall within said chamber having a cross sectional area approximately equal to the combined cross sectional area of the water tubes connected with said header, and means to transmit the outwardly directed pressure upon said movable wall to said outer steam casing whereby tension upon said water tubes due to unbalanced pressure within said floating header is prevented.

3. In a feed water heater having an outer 115

- steam casing, a main header and a floating header therein and a plurality of water tubes secured to and extending between said headers, said headers being provided with 5 water chambers with which said tubes are in communication, a guiding sleeve secured to said floating header, a cylinder having a closed outer wall slidably mounted on said sleeve and defining with said sleeve a chamber 10 communicating with the water space of its respective floating header, the inner face of said closed outer wall being approximately equal to the combined cross sectional area of the water tubes connected with said 15 floating header and means to transmit the outwardly directed pressure upon said closed outer wall to said outer steam casing whereby tension upon said water tubes due to unbalanced pressure within said header 20 is prevented.
4. In a feed water heater having an outer steam casing, a main header secured to said casing, a plurality of floating headers and a plurality of water tubes secured to and 25 extending between each of said floating headers and said main header, each of said headers being provided with a water space with which said tubes are in communication and means defining a chamber secured to 30 each of said floating headers and communicating with the water space thereof, a movable wall of each of said chambers having a cross sectional area approximately equal to the combined cross sectional area of the water tubes connected to its respective floating header, and means to transmit the outwardly directed water pressure upon said movable wall to said outer steam casing whereby tension upon said water tubes due to unbalanced pressure is prevented. 35
5. In a feed water heater having an outer steam casing, a main header secured to said casing, a plurality of floating headers and a plurality of water tubes secured to and extending between each of said floating headers and said main header, each of said headers being provided with a water space with which said tubes are in communication, a guiding sleeve secured to each of said floating headers, a cylinder having a closed outer end wall slidably mounted on said sleeve and defining with said sleeve a chamber communicating with the water space of its respective floating header, the inner face of said closed outer wall being approximately equal to the combined cross sectional area of the water tubes connected to its respective floating header and means to transmit the outwardly directed pressure upon the inner face of said closed outer wall to said outer steam casing whereby tension upon said water tubes due to unbalanced pressure is prevented. 40 45 50 55 60
